UNITED STATES PATENT OFFICE.

BIRD A. ROBERTSON, OF BEN FRANKLIN, TEXAS.

BRUSH-CYLINDER FOR GINS.

1,122,308.

Specification of Letters Patent. Patented Dec. 29, 1914.

Application filed June 8, 1914. Serial No. 843,792.

To all whom it may concern:

Be it known that I, BIRD A. ROBERTSON, a citizen of the United States, residing at Ben Franklin, in the county of Delta and 5 State of Texas, have invented a new and useful Brush-Cylinder for Gins, of which the following is a specification.

The present invention appertains to brush cylinders for gins, and aims to provide 10 novel and improved means for securing the brush sticks in place and for enabling them to be readily removed and replaced.

The present invention also contemplates the provision of means for holding the 15 brush sticks of the cylinder in place, which will be comparatively simple, non-encumbering and inexpensive in construction, as well as being convenient, practical and efficient in its use.

20 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

25 The invention has been illustrated in its preferred embodiment in the accompanying drawing, wherein:—

Figure 1 is an end view of the brush cylinder embodying the present improvements, 30 portions being broken away. Fig. 2 is a fragmental plan view of portions of the cylinder.

The brush cylinder includes a cylindrical frame or body 1 which, in practice, usually 35 consists of a plurality of spaced sections or heads, although for the purposes of the present invention, the frame or body 1 may be considered as a unit.

The body or cylinder proper 1 is provided 40 with an annular series of longitudinal grooves or channels 2 in which are snugly seated or fitted, the sticks 3 of the brushes, which sticks 3 are each provided with a longitudinal series of tufts of bristles 4.

45 In carrying out the present invention, the body or cylinder 1 is equipped at longitudinally spaced points, with transverse grooves or channels 5 between the respective grooves or channels 2. The grooves or depressions 5 are preferably arranged in annular series, and are relatively shallow, while

the grooves or channels 2 are relatively deep. The side walls of the grooves 2, as well as the grooves 5, are preferably parallel and flat, and the grooves or depressions 5 extend 60 to the side walls of the grooves 2.

The brush sticks or bars 3 are provided along their outer corners or edges with chamfered or beveled notches 6, which register or coincide with the respective transverse grooves or channels 5, and the ends of the notches or cut away portions 6 being flush with the sides of the grooves 5.

Seated or fitted snugly within each of the grooves or channels 5, is a transversely arranged latch or clamp 7, which is preferably flush with the periphery of the body or cylinder 1, and which has its ends beveled as at 8, to fit snugly within the respective chamfered or beveled notches 6 of the adjacent brush sticks or bars 3. A screw or other securing member 9 is engaged centrally through each of the latches or clamps 7, and takes into the body or cylinder 1, to hold the latch or clamp tightly in place. 80 The edges of the latches or clamps 7 snugly engage the sides of the grooves 5, to prevent the latches or clamps from rotating or oscillating and the latches or clamps being clamped against the body or cylinder 1, 85 will clamp the brush sticks 3 within their grooves or seats 2, while the beveled ends 8 of the latches or clamps 7 in engaging between the ends of the chamfered or beveled notches 6 of the brush sticks, will prevent 90 the brush sticks from sliding or shifting longitudinally within the grooves 2.

In use, the cylinder bearing the brushes and holding or securing members is applied to the gin in the usual manner, as will be 95 evident to those versed in the art. The latches or clamps will effectively hold the brushes in place, to prevent their radial or longitudinal displacement. Should one or more of the brushes become worn out, or 100 should it be desired to replace one or more of the brushes for any other reason, by loosening the corresponding latches or clamps 7, the desired brush sticks may be loosened so that they be withdrawn longitudinally from the body or cylinder 1, 105 that is, when the latches or clamps 7 are moved outwardly sufficiently to disengage the notches 6 of the brush sticks. The removed brushes may then be replaced, and 110 the replaced brushes may be secured in place by clamping the corresponding latches

or clamps 7 into the respective grooves 5 as above noted. It is to be noted that the clamps or latches 7 when assembled with the body or cylinder and brushes in the manner indicated, will effectively hold the brushes against displacement, and will provide for desirable advantages.

With the present improvement, brushes may be removed and replaced with a minimum expenditure of time and labor.

Having thus described the invention, what is claimed as new is:—

1. In a device of the character described, a cylinder having longitudinal grooves, and having transverse channels between the said grooves, brushes including sticks seated in the said grooves, latches disposed snugly in the said channels and having their ends engaging the brush sticks to hold them within the grooves, and means for clamping the latches within the said channels.

2. In a device of the character described, a cylinder having longitudinal relatively deep grooves and transverse relatively shallow channels between the grooves, brushes including sticks seated in the said grooves,

and having notches coinciding with the ends of the channels, latches fitted snugly within the said channels and having their ends engaging the notches of the brush sticks, and means for clamping the latches within the said channels.

3. In a device of the character described, a cylinder having longitudinal relatively deep grooves, and transversely relatively shallow channels between the said grooves, brushes including sticks seated in the said grooves, and having chamfered notches at their outer corners coinciding with ends of the channels, latches fitted snugly within the said channels and having beveled ends engaging the said notches of the brush sticks, and securing members engaged centrally through the latches and taking into the cylinder.

In testimony that I claim the foregoing as my own, I have hereto affixed my signature in the presence of two witnesses.

BIRD A. ROBERTSON.
